UNITED STATES PATENT OFFICE.

GEORGE JAMES MANSON, OF TORONTO, ONTARIO, CANADA.

METHOD OF CLEANING FIBER-PRESS DIES.

1,413,178.

Specification of Letters Patent. Patented Apr. 18, 1922.

Application filed May 3, 1919. Serial No. 294,627.

(GRANTED UNDER THE PROVISIONS OF THE ACT OF MARCH 3, 1921, 41 STAT. L., 1313.).

To all whom it may concern:

Be it known that I, GEORGE JAMES MANSON, a subject of the King of Great Britain, and resident of the city of Toronto, in the 5 Province of Ontario, Dominion of Canada, have invented certain new and useful Improvements in Methods of Cleaning Fiber-Press Dies, of which the following is a specification.

10 This invention relates to improvements in method of cleaning fiber press dies, and the objects of the invention are to avoid clogging of the drainage surface in a die, and to enable the dies to operate on fibers 15 of a resinous character such as are produced from bark of wood when the bark is ground with the remainder of the wood, and the invention consists in sprinkling the surface of the dies between the pressing operations as 20 hereinafter described in detail in the accompanying specification and drawings.

The drawings show a set of dies and apparatus for carrying out the sprinkling operation.

25 In the drawings:

Figure 1 is a sectional elevation of a fiber press.

Figure 2 is a sectional plan.

Figure 3 is a cross sectional elevation.

30 Figure 4 is a sectional detail of the water feeding means.

Figure 5 is a sectional detail of the retractor and carriage for the sprinkling means.

Figure 6 shows the same parts as in Figure 5 with the retractor and carriage beneath the dies.

Figure 7 is a sectional detail of the dies closed.

Figure 8 is a sectional detail of a portion 40 of the cam track controlling the sprinkling device.

Figure 9 is a sectional view through the controlling valve.

45 In the drawings like characters of reference indicate corresponding parts in all the figures.

Referring to the drawings, A represents a fiber press having an upper die B, a lower die C, and a side or wall die D which are 50 operated by suitable hydraulic means to press a sheet of fiber in the manner well known in the art. In the embodiment illustrated the lower die C is connected to and actuated by hydraulic cylinders 10 which 55 actuate plungers 11 connected to a platform

12 supporting the die. The upper die B is connected to a platform 13 fixedly mounted on the side posts 14, the lower extremities of which are connected by a cross bar 15 to the cylinders 10. The side or wall die D is 60 also actuated by hydraulic means such as the cylinder 16 having plungers 17 connected to opposite sides of the wall die.

In the present operation the closed position will be as indicated in Figure 7 and 65 the open position as shown in Figure 1. The pulp or other fiber stock to be pressed into a sheet or other article may be fed into the conduit 18 which opens into a port 19 in the wall die, the retraction of the wall die 70 over the die B cutting off the port and supply of fiber at the proper point. It will be understood, however, as far as the present invention is concerned the dies and method of operating the same will be of any suitable 75 character.

E represents a sprinkling device reciprocable between the dies B and C when they are separated. The form of sprinkling device I have shown comprises a transversely 80 extending pipe 20 perforated in rows along the top and bottom whereby when the water pressure is on, the surface of both the upper and lower dies will be sprinkled. This pipe is supplied with water with a suitable flexible connection including a telescopic supply pipe 21 extending through a gasket 22 in the end of the pipe 20 connected to a suitable supply pipe 23. The pipe 20 is supported from a reciprocable retractor carriage F having 85 wheels 24 which run in a track 25, the movement of the retractor carriage being controlled by suitable means such as the driving pinion 26 engaging the rack 27 connected to the carriage, the rack receiving 90 additional support from suitable rollers 28.

Means are provided for stripping the pressed sheet from the retractor carriage when outside the die whereby it may be transferred to a suitable conveyor. These 100 means comprise a pivoted stripping member 31 pivotally mounted on the cross shaft 32 and adapted to assume the inclined position shown in Figure 5 as the carriage F passes beneath it whereby on the return motion of 105 the carriage it will strip the sheet of pulp 33 therefrom and permit it to drop onto the conveyor G.

The operation of the sprinkling device is controlled in such a way as to cause it to 110

operate only when it is moving on the return direction across the face of the dies. It is not desirable that the sprinkling should take place on the forward motion, since while the 5 sprinkler is moving in this direction the pressed sheet will be held against the surface of the die. The controlling means which I have shown comprise a valve 35 of any suitable type having a stem 36 normally spring held in open position by means of a spring 37 extending between the collar 38 on the stem 36 and the top of the valve casing 39. The stem 36 carries a roller 40 at the top controlled by a cam track 41. This cam 10 track 41 includes a lower track 42 having a central aperture through which the stem 36 may pass, but through which the roller 40 may not pass, and an upper track 43 which projects beyond the upper track and is 15 formed at one portion with an inclined section 44 which brings it into alignment with the lower track.

On the inward movement the roller 40 runs on the lower track 42; when it reaches the 20 end of this track the spring 37 causes the valve stem to move outwardly, opening the valve and causing the sprinkler to operate on the return movement. While the 25 sprinkler is operating the roller 40 runs on the track 43, passes down the inclined portion 44 to the lower portion 45 of the track 43. On the return movement the roller is 30 prevented from passing up the inclined portion 44 by means of a spring trap member 46 35 hinged to the end of the track 42 and spring held in alignment therewith as shown in Figure 8, whereby when the trap member is 40 in position there will be no passage from the section 45 of the track 43 to the main portion thereof, the trap, however, being free to 45 swing downwardly to permit of movement from the upper track to the lower track.

The operation of the press takes place in the usual way, the pulp stock being fed between the dies and the pressure being exerted by hydraulic means, while the water

is withdrawn through the foraminous surface of the dies, this surface being of any usual character and including a suitable number of grooves and perforated plates of a character 50 well known in the art which will enable the water to be strained, leaving the pulp or fiber between the dies.

Finally the pressed sheet or article is caused by suction to adhere to the upper die 55 when the dies are separated, suction being exerted through the passageways or ports in the die through which the water was withdrawn. When the sheet is in this position the retractor F comes between the dies, the 60 suction is then released to permit the sheet to drop onto the retractor carriage and on withdrawal of the retractor carriage the 65 sprinkler operates as previously described to sprinkle the surface of both the upper and lower die, the sprinkling operation ceasing as soon as the roller passes down the inclined portion 44 to the lower portion 45 of the track 43. When the retractor carriage reaches its outermost position the article is stripped therefrom by means of the 70 pivoted stripping member 31.

As many changes could be made in the above construction and many apparently widely different embodiments of my invention, within the scope of the claim, constructed without departing from the spirit or scope thereof, it is intended that all matter contained in the accompanying specification and drawings shall be interpreted as 75 80 illustrative and not in a limiting sense.

What I claim as my invention is:

The herein described method of operating reciprocating fiber press dies which comprises sprinkling the surface of the die between 85 90 pressing operations.

In witness whereof I have hereunto set my hand in the presence of two witnesses.

GEORGE JAMES MANSON.

Witnesses:

RUSSEL S. SMART,
P. GARROW.
